UNITED STATES PATENT OFFICE

157,312

FAUCET HANDLE

Stephen A. Young, Delphi, Ind.

Application January 30, 1948, Serial No. 144,158

Term of patent 14 years

(Cl. D4—3)

To all whom it may concern:

Be it known that I, Stephen A. Young, a citizen of the United States, residing at Delphi, in the county of Carroll and State of Indiana, have invented a new, original, and ornamental Design for a Faucet Handle, of which the following is a specification, reference being had to the accompanying drawing, forming part thereof.

In the drawings, Fig. 1 is a top plan view of a faucet handle showing my new design. Fig. 2 is an elevational view of such handle and one side thereof. Fig. 3 is a sectional view taken on line 3—3 of Fig. 2.

I claim:

The ornamental design for a faucet handle, as shown.

STEPHEN A. YOUNG.
